UNITED STATES PATENT OFFICE.

GEORGE C. LYNCH, OF NEW YORK, N. Y.

LAMP.

1,096,440.

Specification of Letters Patent. Patented May 12, 1914.

Application filed December 31, 1912. Serial No. 739,580.

To all whom it may concern:

Be it known that I, GEORGE C. LYNCH, a citizen of the United States, residing at and whose post-office address is 323 Fourth avenue, of the city of New York, in the county of New York and State of New York, have invented certain new and useful Improvements in Lamps; and I do hereby declare the following to be a full, clear, and exact 10 description of the invention, such as will enable others skilled in the art to which it appertains to make and use the same.

The object of my invention is to provide an improvement in lamps, having special reference to electric portable, table lamps.

I provide an improved bracket which permits of the shifting of the illuminating portion, including the light proper and the shade, laterally relatively to the base. This 20 I accomplish by a swivel connection between the stationary support and the rotary part or bracket, thereby permitting adjustment without bending the electric wires, which latter action tends to break them and cause 25 short circuits and fire.

In the accompanying drawing Figure 1 shows in side elevation a lamp embodying my improvements. Fig. 2 is a section of the swivel connection and Figs. 3 and 4 show 30 the parts thereof separated.

The lamp 1 is of the portable electric kind such as is ordinarily used on library tables, desks, etc. In the use of these lamps it is frequently desirable to have the base located 35 at a certain point on a table away from the user to provide space for books and papers and at the same time have the light relatively near the user. I have accordingly shown the portable lamp mounted upon a 40 suitable base 2 which is weighted at its rim. The stem 3 is provided at its top with a right angular portion 4 which may be cast integral with the stem or otherwise secured thereto in any manner which holds it rigid 45 in the position shown. At its extremity the angular arm 4 is shown bent upward. The curved bracket 5 supports the cluster of lights 6 and the lamp shade 7 and is swiveled upon the extremity of the arm 4 as at 8. 50 This swivel connection preferably comprises a two part coupling, one of which parts has

a central post 9 provided with a recess 10 to which one of the electric conductors 12 is connected. Surrounding this post I have shown a metallic sleeve 13 in electrical connection with conductor 14. The part 8^a of the coupling is adapted to be connected to the part 8^b by having its post enter a recess 15 of the latter, the recess having a pin 16 to enter the recess 10 and a conductor 17 connected to the pin. This recess is lined with metal as at 18 to form electrical connection with the sleeve 13 and this lining is connected to a conductor 19. Thus provision is made for turning the parts 8^a 8^b relatively 6 without disturbing the circuit through the coupling or twisting the wires.

From the foregoing description it will be seen that without disturbing the position of the base and, in fact, while even placing it 70 farther away from the user, the bracket 5 may be swung upon the arm 4 into the dotted line position or any intermediate position, the weight in the base 2 preventing the lamp from over-turning while bringing the lights 75 directly over the head of the user or at any desired point.

I claim as my invention:—

1. In an electric portable lamp having a base and a stem and a light cluster normally 80 in substantially the vertical plane of the stem, a bracket supporting said light cluster, and a swivel support for said bracket at one side of the vertical plane of said stem, whereby said bracket may be shifted laterally out 85 of alignment with said stem.

2. In an electric portable lamp, the combination with the base and stem and the right angular arm at the top of said stem, of a bracket supported on said arm and constituting the support for the lights and for 90 the lamp shade, and a swivel connection between said arm and said bracket comprising two parts, one of which is formed with a post and the other with a recess to receive 95 said post.

3. In a portable lamp the combination with the base and vertical stem, an arm rigidly secured to said stem, and a bracket on 100 said arm adapted to support the lights and the lamp shade, of a swivel connection between said bracket and said arm, compris-

ing two parts one having a post and the
other a recess to receive said post, a metallic
sleeve on said post and a metallic lining in
said recess, one of said parts having a pin
and the other a socket to receive said pin,
and electric conductors connected to said me-
tallic coverings and said pin and socket.

In testimony whereof, I have signed this
specification in the presence of two subscrib-
ing witnesses.

GEORGE C. LYNCH.
